UNITED STATES PATENT OFFICE.

DYAS SHELTON, OF SANTA ROSA, CALIFORNIA.

VEHICLE-BOLSTER.

SPECIFICATION forming part of Letters Patent No. 255,736, dated March 28, 1882.

Application filed January 3, 1882. (No model.)

To all whom it may concern:

Be it known that I, DYAS SHELTON, a citizen of the United States, residing at Santa Rosa, in the county of Sonoma and State of California, have invented certain new and useful Improvements in Vehicle Bolsters and Plate in Conjunction with a Sand-Board; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to wagon bolsters and plate, in conjunction with a sand-board so arranged that the strain and wear heretofore brought to bear upon the king-bolt and plates by the lateral motion of the vehicle are thrown in part upon and sustained by said bolster, plates, and sand-board.

The ordinary plates with which I am familiar are so arranged that the rocking bolster by its lateral motion and extended play causes said plates to wear at their ends. This is particularly the case in driving a loaded wagon on uneven ground, by means of which the weight of the load is thrown to one side. Another difficulty encountered by this peculiar construction is that the driver on uneven ground is thrown to one side, so as to render it difficult, if not quite impossible, for him to reach the brake. The load thus thrown to one side rests greatly upon the king-bolt and side of the bolster, so that said bolster at length has sufficient play to cut the sand-board, and sometimes they lock. I overcome these difficulties by the mechanism illustrated in the accompanying drawings, in which—

Figure 1 is a front elevation, showing my improvement attached to a sand-board and partially secured thereto by means of a king-

bolt. Fig. 2 is a perspective view of the sand-board plate. Fig. 3 is a front elevation of the 45 bolster, plate, and king-bolt.

The letter A represents the arms of the bolster; A', the front of the elliptical shank, formed of and constituting a part of the bolster. B is the elliptical metallic plate, screwed or otherwise attached to the bottom of the shank A'. C is the sand-board plate, having lugs E E. D is the sand-board. F is the king-bolt. G represents the circular slot in the sand-board to receive the king-bolt. The letters f indicate the screws, tending to secure the sand-board plate C to the sand-board D. m m are the slots in the sand-board to receive the screws f or other connecting means.

In the drawings it will be seen that the lugs E E of the sand-board lap over two sides of the plate B, by means of which (assisted by the king-bolt) said plate is held firmly in the recess in the sand-board plate. The bolster A, being secured to the plate B, is also necessarily held. The bolster A and plate B turn freely in the recess in the sand-board plate C. The lugs E E are of sufficient width to keep the plate B from escaping.

Having thus described my invention, I claim as new and desire to secure by Letters Patent—

In a vehicle, the sand-board D, having plate C connected thereto by means of screws f, said plate having lugs E E, in combination with elliptical plate B, which is attached to elliptical shank of bolster A', said bolster having tapering arms A A, the whole being secured by the king-bolt F, in the manner and for the purposes set forth.

In testimony whereof I affix my signature in presence of two witnesses.

DYAS SHELTON.

Witnesses:

ALBERT G. SHANNON,
WILLIAM W. PORTER.
